(57) **CLAIM**

The ornamental design for a carrier for golf clubs, as shown and described.

DESCRIPTION

FIG. 1 is a top perspective view of a carrier for golf clubs showing my new design;

FIG. 2 is a left perspective view thereof;

FIG. 3 is a right perspective view thereof;

FIG. 4 is a top plan view thereof;

FIG. 5 is a rear elevational view thereof;

FIG. 6 is a bottom perspective view thereof;

FIG. 7 is a top plan view thereof, showing a drawer thereof in an open position; and,

FIG. 8 is a bottom plan view thereof.

The broken line showing of the drawer of the carrier for golf clubs is for the purposes of illustrating environment and forms no part of the claimed design.
